UNITED STATES PATENT OFFICE.

HENRY M. NORRIS, OF PHILADELPHIA, PENNSYLVANIA, ASSIGNOR TO THE
APPLETON MANUFACTURING COMPANY, OF PENNSYLVANIA.

GRINDING AND POLISHING ATTACHMENT FOR SEWING-MACHINES.

SPECIFICATION forming part of Letters Patent No. 544,190, dated August 6, 1895.

Application filed September 22, 1894. Serial No. 523,825. (No model.)

To all whom it may concern:

Be it known that I, HENRY M. NORRIS, a citizen of the United States, residing in the city and county of Philadelphia, State of Pennsylvania, have invented a new and useful Improvement in a Grinding and Polishing Attachment for Sewing-Machines, which improvement is fully set forth in the following specification and accompanying drawings.

10 My invention consists of a grinding-wheel adapted to be attached to a sewing-machine and operated by a moving member of the same, the same embodying novel features, as will be hereinafter set forth.

15 Figure 1 represents a perspective view of a grinding attachment to a sewing-machine embodying my invention. Fig. 2 represents a side elevation of a portion of the same on an enlarged scale. Fig. 3 represents a section thereof on line $\alpha\alpha$, Fig. 2. Fig. 4 represents an end view of a portion thereof. Fig. 5 represents a perspective view of a detached portion. Fig. 6 represents a perspective view of a polishing-wheel and the shaft thereof, as will 25 be hereinafter referred to.

Similar letters of reference indicate corresponding parts in the several figures.

Referring to the drawings, A designates a standard, on which is supported the horizontal 30 boss B, in which is mounted the shaft C, the latter having secured to it on one end thereof the friction-pulley D, which is adapted to contact with the driving-pulley or other suitable rotating member of a sewing-machine, as shown in Fig. 1. The other end of said shaft 35 has secured to it an emery or other grinding wheel E, which is partly covered or encircled by the hood F, which is formed with or attached to the boss B and standard A and serves as a guard against dust, &c. Connected with the said hood or guard at the lower portion thereof is an outwardly-projecting lip G, which has an inclined upper face and to which is adjustably attached the table H, on which 40 scissors or other articles to be sharpened may be supported while presented to the uncovered portion of the wheel E, as also shown in said Fig. 1, it being noticed that said table H has a depending limb I in which is a longitudi-

nal slot K, the same extending in oblique direction to receive the screw L, which is fitted to said lip G.

The side of the limb J has an inclined shoulder G', which rests on the inclined face of the lip G, whereby the table always maintains a horizontal position and presents the same angle to the periphery of the wheel E in all of its adjusted positions.

It will be noticed that the wheel is supported on one end of the shaft C and its outer side projects beyond the peripheral rim of the hood or guard F, by which provision implements, especially scissors, may be sharpened close to the pivot of the same without interference of said hood or guard, and said side is also presented for sharpening purposes when so desired.

In order to provide for the attachment and removal of the wheel E to and from the shaft C the end of the latter is formed with an opening E' to receive the screw M, the wheel being placed on said end and having washers on opposite sides of its center, whereby when the screw is tightened the wheel is firmly held in position. When said screw is removed I 75 may attach the polishing or buffer wheel N to the shaft C, said wheel having its supporting-spindle P provided with a threaded neck Q, which is adapted to enter the opening in the shaft C previously occupied by the screw M, the said wheel N being firmly held on said shaft P owing to the tapering and threaded nature of the latter, as will be shown in Fig. 4.

The base of the standard A has a vertical slot R therein for the reception of the set-screw S, whereby the pulley may be adjusted to the operating-wheel on the sewing-machine and the said standard firmly secured to the table thereof.

In practice the standard A, hood or guard F, and lip G are formed integral of cast metal.

It is evident that when the parts are in position on a sewing-machine the wheel will be rotated, thus providing a convenient device for sharpening or grinding scissors and other implements and for polishing purposes, the power of the machine being communicated to said wheel, the device being of light, strong,

durable, and inexpensive construction, it being easily applied and removed to and from the machine.

The boss B incloses the shaft C and prevents the same from being exposed to contact of the hand and causing oil to fly toward or from the operator.

Having thus described my invention, what I claim as new, and desire to secure by Letters Patent, is—

1. In a grinding and polishing attachment for a sewing machine, a standard having an outwardly-projecting lip with an inclined upper face, a table having a depending limb, with an oblique slot therein, and provided on its side with an inclined shoulder adapted to rest on the inclined face of the said lip, and

a screw for fastening said table to said lip, said parts being combined substantially as described.

2. A standard adjustable on a support and having a boss and a hood connected therewith, a shaft journaled in said boss, carrying a grinding wheel, said wheel extending beyond said hood, a lip on said standard having an inclined upper face, a table having a depending limb with a slot therein and a shoulder on its side and a screw passing through said slot in said lip, said parts being combined substantially as described.

HENRY M. NORRIS.
